UNITED STATES PATENT OFFICE.

GEORGE N. TODD, OF CHICAGO, ILLINOIS, ASSIGNOR TO THE TODD COTTON HARVESTER COMPANY, OF ILLINOIS.

COMBINED PICKER-STEM AND CLEANER.

SPECIFICATION forming part of Letters Patent No. 423,539, dated March 18, 1890.

Application filed September 14, 1887. Serial No. 249,630. (No model.)

To all whom it may concern:

Be it known that I, GEORGE N. TODD, a citizen of the United States, residing in Chicago, county of Cook, and State of Illinois, have invented certain new and useful Improvements in Combined Picker-Stems and Cleaners, of which the following is a specification.

This invention relates to improvements in combined picker-stems and cleaners for cotton-harvesters, in which the stem and cleaner are permanently connected together and simultaneously projected into the cotton-plant, and has for its prime object to so construct the device that the cotton gathered by the stem while in the bush will be immediately stripped therefrom and transferred to the cleaner, from whence it may afterward be removed in any well-known and convenient manner, whereby greater speed may be given the picker-stem in its axial rotation and less speed in its movement of translation than in any of the prior constructions, thereby increasing the effectiveness of the cotton-harvester as a whole. I attain this object by the devices illustrated in the accompanying drawings, in which—

Figure 1 represents a side elevation of a picker-stem and cleaner embodying my invention; Fig. 2, a transverse section thereof.

Similar letters of reference indicate the same parts in the several figures of the drawings.

Referring by letter to the accompanying drawings, A represents a portion of the picker-stem supports mounted in the usual way in a cotton-harvester frame for imparting to said stems a movement of translation into and through the bushes, so that the stems may first gather the cotton and afterward have the same removed therefrom while out of engagement with the plants, and as the particular means for producing such movements do not form a part of this invention, and as the operation of these machines is so well understood, I do not deem it necessary to herein illustrate and describe the same. Screwed or otherwise rigidly secured to this support is the cleaner, consisting of a frame circular in cross-section and composed of a series of rings or disks C, united at the tops and bottoms thereof, respectively, by longitudinal bars D and E, the latter of which has projecting from one side thereof between the

disks the teeth F, formed concentrically with 55 said disks, the entire cleaner-frame, by reason of its rigid connection with the support A, being held in a fixed position at all times relative thereto. Passing axially through said cleaner-frame and journaled therein, or 60 in the support A, is a central shaft G, having a beveled gear H, secured to the inner end thereof, by which a rotary motion is imparted thereto, said shaft being also provided with circumferential series of radially-projecting teeth I, each series occupying the space between two disks or rings C, the points thereof lying substantially flush with the peripheries of said disks or rings, as clearly shown in Fig. 2.

In practice the combined picker-stem and cleaner is introduced into the plant, as heretofore stated, the picker-stem—that is to say, the toothed shaft—having a continuous rotation upon its own axis and about the axis of its support throughout the operation of the machine, as a result of which the teeth of said stem will gather the cotton and deposit it upon the toothed edge of the lower bar of the cleaner, which has a stripping effect 80 upon said teeth, the accumulated cotton being afterward removed from the cleaner, when out of engagement with the plant, by any suitable wiper or cleaning device employed for that purpose.

Having described my invention, what I claim, and desire to secure by Letters Patent, is—

1. An internal revolving shaft carrying picking-teeth, and a movable support therefor, in combination with a stationary cleaner attached to and moving with said support, having a toothed bar on one side thereof opposing said teeth, whereby the cotton will be gathered by the said teeth and stripped therefrom by and deposited on said bar, substantially as described.

2. The movable support and the cleaner rigidly secured thereto, said cleaner being composed of disks or rings united at their peripheries by a toothed bar, in combination with the internal revolving shaft carrying circumferential series of picker-teeth, substantially as described.

GEORGE N. TODD.
